ANGLE VALVE

Lawrence F. Luckenbill and Richard A. Stultz, Decatur,
Ill., assignors to Mueller Co., Decatur, Ill.

Filed Nov. 23, 1971, Ser. No. 101,619

Term of patent 14 years

Int. Cl. D23—01

U.S. Cl. D23—19

FIG. 1

FIG. 2

FIG. 3

FIG. 4

FIG. 5

FIG. 1 is a side elevational view of an angle valve embodying our new design;

FIG. 2 is an end elevational view taken from the right of FIG. 1;

FIG. 3 is a bottom plan view of FIG. 1;

FIG. 4 is an end elevational view taken from the left of FIG. 1; and

FIG. 5 is a top plan view of FIG. 1.

We claim:

The ornamental design for an angle valve, as shown.
